HONING MACHINE

**Earnest Y. Seborg, Rockford, Ill., assignor to
Barnes Drill Co., Rockford, Ill., a corporation
of Illinois**

Application September 13, 1943, Serial No. 502,135

10 Claims. (Cl. 51—34)

The invention relates to machines for operating on cylindrical surfaces and more particularly to honing machines.

Both internal and external cylindrical surfaces are commonly finished by a honing operation in which a cylindrical abrasive tool or hone is repeatedly traversed over the surface to be finished. As is characteristic of any abrasive operation, the finished surface is marked by minute grooves corresponding to the paths followed by the individual abrasive particles of the tool.

While the grooves produced by the abrasive particles of honing tools are of microscopic size their orientation is an important factor in determining the characteristics of the finished surface. In certain classes of work, as for example, internal combustion engine cylinders a surface having helical grooves intersecting to produce a "cross-hatch" effect is advantageous. A finish of this type is produced by continuously relatively rotating and simultaneously relatively reciprocating the tool and work in predetermined timed relation.

For other types of work, of which recoil and recuperator cylinders for gun carriages are an example, it is preferred that the grooves produced by the abrasive particles parallel the longitudinal axis of the work. This type of finish is produced by an operation commonly known as "lapping" or "straight-line honing" in which the tool and work are relatively reciprocated axially without rotation. To prevent the abrasive particles from retracing the same paths, the tool and work are intermittently indexed that is, one or the other is rotated through a relatively small angle at one or both ends of the reciprocatory stroke.

One object of the invention is to provide an improved honing machine in which the tool and work may be relatively rotated continuously or indexed intermittently by the same prime mover.

Another object is to provide a novel system for controlling the spindle driving motor of a honing machine to adapt it for rotating the tool spindle continuously or indexing it in small, accurately measured steps as required by the particular surface finish to be imparted to the workpiece.

Other objects and advantages of the invention will become apparent from the following detailed description of the preferred embodiment illustrated in the accompanying drawings in which:

Figure 1 is a side elevational view of a honing machine embodying the features of the invention.

Fig. 2 is a diagrammatic view of the tool supporting head of the machine.

Fig. 3 is a sectional view taken in a vertical plane substantially on the line 3—3 of Fig. 1.

Fig. 4 is a circuit diagram of the electrical operating and control circuits of the machine.

For purposes of illustration the invention has been shown as applied to a horizontal honing machine of the type in which a cylindrical abrasive tool or hone H is rotated and simultaneously reciprocated in the cylindrical bore of a stationarily supported workpiece W. It will be understood, of course, that the invention may be incorporated in other types of honing machines. It is also to be understood that various changes and modifications in the form, construction and arrangement of the parts may be made without departing from the spirit and scope of the invention as expressed in the appended claims.

Referring to Fig. 1 of the drawings, the machine selected to illustrate the invention comprises generally an elongated base including a bed section 5 and a work supporting section 6 bolted or otherwise rigidly secured together in end-to-end relation. Guide bars 7 (Fig. 3) mounted on the side walls of the bed section in spaced parallel relation form a horizontal track or guideway for a translatable tool supporting head 8. A spindle 9 journaled in the head is fitted with an elongated tubular driver 10 adapted to carry the hone H at its other end. The hone may thus be traversed axially through the workpiece W which is supported on a base section 6 by suitable fixtures 11.

The hone H may be of the conventional expanding and contracting type and as herein shown is adapted to be expanded by a pressure fluid operated actuator. The actuator, in this instance, comprises a piston 15 (Fig. 2) working in a cylinder 16 and connected by a rod 17 with expanding mechanism of well-known construction incorporated in the hone. Pressure fluid is supplied to the closed end of the cylinder 16 by a pump P driven by an electric motor M. A relief valve V determines the pressure of the fluid supply to the cylinder while a conventional two-position control valve actuated in any suitable manner as by a solenoid SO—1 (Figs. 1 and 4) is arranged to connect the cylinder alternately with the pump and with a drain line 18 leading to a sump or reservoir R within the head. Fluid is withdrawn from the reservoir by the pump P through an intake line 19.

Upon delivery of fluid under pressure to the cylinder 16, the piston 15 is forced outwardly or to the right as viewed in Fig. 2 to expand the

hone H into operative engagement with the work. Connection of the cylinder with the drain line relieves the pressure on the piston and a spring 20 interposed between the piston and a stationary part of the head acts to shift the piston and its rod 17 toward the closed end of the cylinder thus permitting the hone to contract in well-known manner.

In the particular machine illustrated, the hone H is traversed axially of the work by reciprocation of the head 8. Reciprocatory movements are imparted to the head by an electric motor M-1 through a reversible hydraulic transmission 21 of any suitable character. The hydraulic transmission is drivingly connected with a drum 22 journaled at one end of the bed section 5. Cables 23 and 24 operatively connect the head with the drum, the cables being oppositely wound on the drum and one of them, in this instance the cable 24, being looped over a sheave 25 rotatably supported at the opposite end of the bed section 5. Control of the transmission 21 to effect the reciprocation of the head is effected in well-known manner by control devices actuated incident to such reciprocation.

As stated heretofore, a honing operation requires either constant rotation or intermittent indexing of the honing tool in addition to the axial translation effected by the reciprocation of the head 8. In accordance with the invention such movements are imparted to the tool by a single prime mover, preferably an electric motor M-2 herein shown as mounted on the head 8 and drivingly connected with a spindle 9 by a train of gears 26 (Fig. 2).

Preferably the hone expanding actuator and fluid supply means therefor including the pump P, the motor M and the control valve V-1 as well as the spindle driving motor M-2, are all mounted on the head 8 and reciprocable therewith (Fig. 4). Electric current is supplied to the motors, the valve actuating solenoid and other control elements through a series of contact members carried by and reciprocable with the head 8 and slidably engaging a like series of conductor bars extending longitudinally of the bed 5. In the exemplary machine six contact members 31, 32, 33, 34, 35 and 36 carried by an arm 37 projecting from one side of the head 8 are arranged to cooperate respectively with conductor bars 37, 38, 39, 40, 41 and 42 supported on brackets 43 at the side of the bed 5.

The operating requirements of the spindle driving motor M-2 differ substantially for straight-line honing as compared with ordinary continuous honing. Thus in continuous honing considerable power is required to rotate the hone while it performs its metal removing function. In straight-line honing, on the other hand, less power is required to rotate the hone but the degree of rotation imparted thereto in each indexing cycle as well as the interval between cycles must be accurately controlled. The present invention provides a novel control circuit whereby the machine may be conditioned selectively for either type of operation by the manipulation of simple manually operable switching devices.

Referring to Fig. 4 of the drawings, current for operating the motors and control devices of the machine is taken from a power line comprising conductors L-1, L-2 and L-3. A branch of the power line comprising conductors 45, 46 and 47 constitutes the supply circuit for the spindle driving motor M-2. This circuit includes switches MF-1, MF-2 and MF-3 actuated by

a forward running relay MF and switches MR-1, MR-2 and MR-3 actuated by a reverse running relay MR arranged to selectively connect the line conductors with the conductor bars 37, 38 and 39 so as to effect either forward or reverse rotation of the motor. Brushes 31, 32 and 33 coacting with the conductor bars 37, 38 and 39 are connected with the motor M-2 by conductors 48, 49 and 50.

10 Resistances 1R, 2R and 3R are connected respectively in the supply conductors 45, 46 and 47 to reduce the voltage of the current supplied to the spindle driving motor M-2 when the machine is used for straight-line honing. The spindle indexing action of the motor may thus be controlled with a high degree of accuracy and injury to the motor by successive starting and stopping thereof is effectually avoided. For continuous honing, the resistances 1R, 2R and 3R are shunted by the closure of switches R-11, R-12 and R-13 actuated by a relay R-1 so that the current at full line voltage is supplied to the motor.

To condition the machine for either type of 25 operation, simple manually operable switching means is incorporated in the control circuit so that the machine attendant may readily effect the necessary changes. The switching means as herein shown, comprises a pair of selector switches 30 S-1 and S-2 adapted to be operated by a common actuator and arranged so that when either switch is opened the other is closed. The switch S-1 controls the circuit of the resistance shunting relay R-1 while switch S-2 controls a timer 35 T. More particularly switch S-1, when closed, establishes a circuit for the relay R-1 so that the relay is energized when the machine is started and shunts the resistances 1R, 2R and 3R to condition the machine for continuous honing.

40 The timer T may be of any suitable type having a timing switch T-1 opened and closed periodically at accurately timed but adjustably variable intervals. The selector switch S-2, when closed, establishes a circuit to enable the timer switch to effect intermittent energization and de- 45 energization of one or the other of the running relays MF or MR so that the intermittent starting and stopping of the spindle driving motor M-2 is effected entirely automatically under control of limit switch LS-2 of timer T. The circuits established by the switches S-1 and S-2 will be described in greater detail hereinafter.

The motor M-2 is preferably equipped with a 50 brake of the usual type adapted to be released by a solenoid SO-2 substantially simultaneously with the starting of the motor. In the exemplary embodiment the brake and solenoid are enclosed in a housing at one end of the motor M-2 as shown in Fig. 2. To insure proper release of the brake, provision is made for supplying operating current to the solenoid SO-2 at full line voltage regardless of the voltage of the current supplied to the motor. The solenoid is accordingly connected in a circuit separate from the spindle motor circuit.

55 Operations of the brake solenoid SO-2 and the spindle driving motor M-2 are coordinated by means of a control relay R-2 connected in the motor circuit. The relay becomes energized 60 when the motor is started and closes switches R-21 and R-22 controlling the solenoid circuit. In order to enable the relay R-2 to function properly at either high or low voltages, switch means is provided for connecting the relay 65 to the motor circuit either directly or in series

with resistors 4R and 5R. The switch means as herein shown comprises a conventional manually operable double pole switch S-3.

The resistors 4R and 5R may be of any suitable character. To insure a sufficient flow of current to energize the relay, one resistor, in this instance the resistor 5R, is normally shunted by a switch R-23 actuated by the relay R-2. When the relay is energized, the shunt is removed thereby increasing the resistance of the relay circuit to prevent the relay from overheating. A voltage responsive safety device 51 which may be of any suitable and well-known type is arranged to open the relay circuit and thus prevent damage to the relay in the event that the switch S-3 is improperly set when the motor is operated at high voltage.

A second branch of the main supply line comprising conductors 52, 53 and 54 supplies operating current to the head reciprocating motor M-1, the pump driving motor M, the hone expansion control solenoid SO-1 and the brake solenoid SO-2. These conductors are connected and disconnected from the supply line conductors by switches R-31, R-32 and R-33 actuated by a control relay R-3.

Conductors 55 and 56 connect the conductors 52 and 53 directly with the conductor bars 40 and 41 for supplying current to the pump motor M and the brake solenoid SO-2. The contact members 34 and 35 coacting with these conductor bars are connected directly with the motor M and, through the switches R-21 and R-22, with the solenoid SO-2.

Branch line conductor 54 is connected in a circuit including switches MF-4 and MR-4 of the running relays MF and MR previously described, a manually operable selector switch S-4, conductor bar 42, contact member 36 and the hone expansion control solenoid SO-1. Thus with the switch S-4 set in one position the solenoid circuit is established only when both motors M-1 and M-2 are running, that is, when switches R-31, R-32 and R-33 and one or the other of switches MF-4 or MR-4 are closed. With switch S-4 set in its alternate position the solenoid circuit is switched from the branch line conductor 54 to conductor 52 so that the solenoid SO-1 is energized when the motor M-1 is running. The hone can therefore be expanded for adjusting purposes or for straight line honing when the spindle 9 is not rotating.

As shown in Fig. 4, the timer T and the control relays, with the exception of the relay R-2, are connected in a low voltage control circuit and provided with conveniently accessible switches by which the operating functions of the machine may be controlled. Current is supplied to the control circuit through a step-down transformer TF connected with the main power line.

To place the machine in operation the head reciprocating motor M-1 and the pump driving motor M are started by momentary closure of a push button actuated starting switch S-5. Upon closure of this switch relay R-3 becomes energized and closes the motor switches R-31, R-32 and R-33 to establish the supply circuit for the motors. Relay R-3 also completes a holding circuit for itself independent of the starting switch by closing a switch R-34.

A motor M-3 driving a coolant pump (not shown) is also started at this time by momentary actuation of a switch S-6. This switch completes a circuit for a relay R-4 which closes switches R-41, R-42 and R-43 to connect the

motor M-3 to the power line. The relay also establishes a holding circuit for itself by closing a switch R-44.

It will be understood that a honing operation 5 may be performed with the hone rotating in either direction. The direction of rotation is determined by the setting of a manually operable double pole switch S-7 arranged to connect one or the other of the running relays MF or MR in 10 the control circuit. As shown, the switch is set to connect up the forward running relay MF.

When the machine is to perform an ordinary honing operation, selector switches S-1, S-2 and S-3 are set in the position shown in Fig. 15 4 of the drawings. With switch S-1 closed, actuation of the starting switch S-5 results in the energization of the relay R-1 which shunts the resistances 1R, 2R and 3R from the supply circuit of the spindle driving motor. Relay R-1 20 also prepares a holding circuit for the selected running relay by closing a switch R-14 and interrupts the timer operating circuit by opening a switch R-15.

An operating cycle may now be initiated by 25 momentary actuation of a cycle starting switch S-8. Operation of this switch is usually effected by a manual control member which simultaneously sets the control devices associated with the head reciprocating mechanism so as to initiate forward movement of the head. Closure of the switch S-8 completes a circuit for the selected running relay, relay MF in the instant case, which becomes energized and closes the switches MF-1, MF-2 and MF-3 for driving 30 the spindle motor M-2 in a forward direction. Relay MF also actuates the switch MF-4 to energize the hone expansion solenoid SO-1 and initiate expansion of the hone as before explained. Another switch MF-5, actuated by the relay MF 35 completes a holding circuit for the relay independent of the starting switch.

Relay R-2 is energized in parallel with the motor M-2 and closes its switch R-22 to energize the brake releasing solenoid so that the motor may operate. Relay R-2, by opening switch R-23, removes the shunt from the resistor 5R and thus reduces current flow in the relay winding to a minimum.

After the cycle is started in the above manner, 50 the honing operation proceeds automatically under the control of the usual reciprocation controlling devices provided in honing machines of the type disclosed. During this cycle, the honing tool is traversed repeatedly from one end of the work to the other in a working stroke while the motor M-2 rotates the hone in timed relation to such reciprocation. To terminate the cycle, the action of the reciprocating controls are modified 55 so as to effect withdrawal of the hone from the work and to stop the head in a withdrawn position. The modification of the controls is effected in well-known manner by energization of a pull-out solenoid SO-3. To energize the solenoid, a switch S-9 is actuated manually or in any other suitable manner to complete a circuit for a control relay R-5 which on energizing closes a switch R-51 to complete the circuit for the solenoid. A switch S-10 mechanically coupled with the switch S-9 opens the holding circuit for the 60 running relay MF to stop the spindle driving motor M-2 while the hone is being withdrawn. As the head 8 approaches its fully withdrawn position, the circuit of the relay R-5 is interrupted by the opening of a limit switch LS-1 thus permitting the control devices to return to 65 70

their normal position in readiness for the succeeding operating cycle.

The operation of the machine may be interrupted at any point in the cycle, when desired, by actuation of a stop switch S-11 which opens the circuit for the relays R-3 and MF. The relays, in turn, interrupt the supply circuit for the motors M, M-1 and M-2. The spindle driving motor M-2 may be stopped at any time without interrupting the operation of the motors M and M-1 by actuating a stop switch S-12. A third stop switch S-13 is provided for stopping the coolant pump motor.

When the selector switch S-7 is set in its alternate position, the spindle driving motor M-2 drives the hone in the reverse direction. The operations involved in starting and stopping a machine, under these conditions, are exactly the same as those described above for forward running except that the relay MR is energized instead of relay MF and the holding circuit is completed by way of a switch MR-5.

As explained heretofore, the machine is conditioned for straight-line honing by actuation of the switches S-1, S-2 and S-3. More particularly these switches are set in their alternate position with switch S-1 open and switch S-2 closed. The opening of switch S-1 interrupts the circuit of the relay R-1 and consequently switches R-11, R-12, R-13 and R-14 remain open and switch R-15 remains closed. When the spindle driving motor is started by closure of the switch S-8, as previously described, current is supplied to the motor at reduced voltage through the resistances 1R, 2R and 3R. Moreover, since switch R-15 remains closed, an operating circuit is completed for the timer T which accordingly acts to periodically open and close the switch T-1.

Under the conditions above described, the usual holding circuit for the selected running relay MF or MR cannot be established due to the open condition of the switch R-14. An alternate circuit for the relay is established however, by way of the timer switch T-1, a limit switch LS-2 and the closed selector switch S-2. Limit switch LS-2 may be arranged for closure by the head 8 in its advance from initial position at the beginning of the operating cycle. Preferably, the arrangement is such that the switch LS-2 is closed at the upper limit of the working stroke and remains closed until the head is withdrawn to retracted position.

The intermittent opening and closing of the timing switch T-1 energizes and deenergizes the selected running relay MR or MF which acts to start and stop the spindle driving motor M-2 intermittently. In practice, the timer is ordinarily set to initiate the operation of the motor substantially at the instant the hone reaches one end of its reciprocatory stroke. The motor operating cycle, which is determined by the closed interval of the switch T-1, is usually timed to provide for indexing the hone through a predetermined angle which may be just sufficient to prevent any abrasive particle of the tool from retracing its path across the work. Since the motor is operated on low voltage current, the starting and stopping may be effected with a high degree of precision thus insuring uniformity of the indexing steps.

Selector switch S-3, when closed for straight-line honing, connects control relay R-2 directly to the supply circuit of the spindle driving motor so that proper operation of the relay is insured at

the low voltage supplied to the motor under these conditions. Relay R-2, as heretofore explained, closes the high voltage current of the brake releasing solenoid SO-2 which is therefore enabled to release the brake promptly and permit instantaneous starting of the spindle driving motor M-2.

The operating cycle of the machine may be interrupted by actuation of the withdrawal switches S-9 and S-10 in exactly the same manner as above described for continuous honing. Likewise, the machine may be stopped at any point in the cycle by operation of the stop switch S-11. Switch S-10, however, is ineffective to control the spindle driving motor at this time as the motor is solely under control of the timer switch T-1.

It will be apparent from the foregoing that the invention provides a honing machine of novel and improved construction in which the honing tool and work may be relatively rotated continuously or indexed intermittently by a single prime mover. The machine may be conditioned for either type of operation by manipulation of simple control devices which act to establish suitable operating and control circuits for the type of operation required. Accurate indexing is insured and the spindle driving motor is protected from injury by the low voltage operation of the motor for indexing the hone. For ordinary honing, however, full voltage is supplied to the motor so that ample power is available to drive the tool while it performs its metal removing function.

I claim as my invention:

1. A honing machine having, in combination, a support for a honing tool, a support for work to be operated on by the tool, power actuated means for relatively reciprocating the tool and work supports, a motor operable to relatively rotate the tool and work, and control means for said motor settable selectively to cause the motor to effect such rotation either continuously or in intermittent steps.

2. The combination in a honing machine having relatively rotatable and reciprocable tool and work supports, an electric motor operable to effect the relative rotation of the tool and work, control means settable selectively to establish either a continuously or intermittently closed operating circuit for said motor, and means operative to quickly stop the motor whenever the operating circuit is opened.

3. The combination in a honing machine having relatively rotatable and reciprocable tool supports, of an electric motor operable to effect the relative rotation of the tool and work, control means operable selectively to establish either a high voltage or a low voltage circuit for said motor, a control device operable to open and close said low voltage circuit intermittently, and means operating in timed relation to the opening of said circuit for quickly stopping said motor.

4. The combination in a honing machine having relatively rotatable and reciprocable tool and work supports, of an electric motor operable to effect the relative rotation of the tool and work, control means operable selectively to establish either a high voltage or a low voltage operating circuit for said motor, and a control device operable to open and close said low voltage circuit intermittently.

5. A honing machine having, in combination, a support for a honing tool, a support for work to be operated on by the tool, power actuated

means for relatively reciprocating the tool and work supports, an electric motor operable to relatively rotate the tool and work, means operable selectively to establish either a high voltage circuit or a low voltage circuit for said motor, a timing device, and means operable simultaneously with said selectively operable means for placing the low voltage circuit under the control of said timer.

6. The combination in a honing machine having relatively rotatable and reciprocable tool and work supports, of an electric motor operable to effect the relative rotation of the tool and work, control means operable selectively to establish either a high voltage or a low voltage operating circuit for said motor, a brake actuating solenoid associated with said motor, a high voltage circuit for said solenoid, and a control relay connected in circuit with said motor and operable simultaneously therewith to control the solenoid circuit.

7. The combination in a honing machine having relatively rotatable and reciprocable tool and work supports, of an electric motor operable to effect the relative rotation of the tool and work, control means operable selectively to establish either a high voltage or a low voltage operating current for said motor, a brake actuating solenoid associated with said motor, a high voltage circuit for said solenoid, a relay for controlling the solenoid circuit, a resistance coil, and switch means operable selectively to connect said relay to the motor circuit either directly or in series with said resistance coil to enable the relay to function at either high or low voltage.

8. In a honing machine, in combination, a work support, a support for an expansible and contractible honing tool, an electric motor for relatively reciprocating said support, a second electric motor for relatively rotating the tool and work, power actuated means for expanding the tool, a solenoid controlling said power actuated means, and switch means operable to establish alternate energizing circuits for said solenoid, 5 one of said circuits being closed only when both of said motors are running and the other of said circuits being closed when one of the motors is running.
9. In a machine of the class described, in combination, a support for a cylindrical abrasive tool, a support for work to be operated on by the tool, means operable to relatively reciprocate the tool and work axially of the tool, a motor operable to rotate the tool about its axis, and 10 a timing device operative automatically to start and stop said motor periodically.
10. In a machine of the class described, in combination, a support for a cylindrical abrasive tool, a support for work to be operated on by the tool, means operable to relatively reciprocate the tool and work axially of the tool, an electric motor operable to rotate said tool about 15 its axis, a circuit for said motor, timer actuated control device operative to open and close said circuit intermittently, and means operative to quickly stop said motor upon the opening of said circuit.

EARNEST Y. SEBORG.
